UNITED STATES PATENT OFFICE.

JOHN EMERSON SCOTT, OF LONG BEACH, CALIFORNIA.

SHOE LINING.

Application filed July 26, 1927. Serial No. 208,470.

This application is a continuation in part of my co-pending application, Serial Number 149,847, filed November 22, 1926.

An object of my invention is to provide a 5 seamless lining for a shoe which will greatly add to the comfort of the wearer.

Another object of my invention is to provide a seamless upper and lining which can be entirely completed before it is lasted and 10 the sole placed thereon.

An advantage of my novel shoe construction is that the stitching machine can extend into the shoe upper from the top or bottom thus making it possible to stitch any 15 portion of the upper.

A further object of my invention is to provide a seamless shoe lining which is provided with a retainer at the rear thereof, or any other portion, or all over the back of 20 the lining to prevent stretching of portions thereof, and to hold it in the shape, and to the size formed.

Other objects, advantages, and features of invention may appear from the accompanying drawing, the subjoined detailed description, and the appended claims.

In the drawing:

Fig. 1 is a plan view of the leather piece from which the seamless lining is formed.

Fig. 2 is a side elevation of the lining after 30 having been formed.

Fig. 3 is a side elevation of the lining with the cuts shown therein to form the tongue.

Fig. 4 is a view similar to Fig. 3 but with 35 the lining shown wrong side out.

Fig. 5 is a side elevation with parts broken away of the shoe upper.

Fig. 6 is a bottom plan view of the assembled shoe upper.

Fig. 7 is a side elevation of the completed shoe.

Referring more particularly to the drawing:

An elliptical piece of material 1 which 45 may be leather, cloth, fabric, or any other suitable material is placed in a machine and is formed into the shape shown in Fig. 2. This process is usual and well-known in the art. During this step of forming the lining, the lower edge of the piece 1 is slightly crimped or creased, as at 2, in order that the material may conform to the shape of the die or form, but the upper, useful portion of the lining is smooth and free of any 50 crimps or wrinkles.

In order that the shape of the lining 1 be held during the subsequent steps in the process of manufacture, I secure a retainer strip 3 to the material. This strip may be cemented, stitched, or otherwise suitably secured to the lining. It is obvious that this strip may be formed in various ways. A single narrow strip may be utilized, or a plurality of strips, or a single side strip may be employed if it is found desirable and necessary. If it is desired, the entire lining 55 may be covered with a retainer.

The lining is now cut along the line 4 to provide the top opening of the lining through which the foot is inserted. To 60 keep the lining from stretching, the retainer 3 may be stitched along the lower edge thereof, as at 5, or may be sewed in place by the stitching used to hold the upper and lining together, or by the stitching 65 which secures the overlays or the like in position. In Fig. 4 the tongue portion 6 has been cut off as is necessary when an oxford is formed, whereas, in Fig. 3 it is left long as is necessary when a high shoe 70 is formed.

After the upper and lining have both been separately formed, the lining is placed inside of the upper and the two are stitched together adjacent the tops thereof, and 75 around the tongue, as shown at 7, and such other stitching as may be necessary to complete the upper. That is, the upper and lining are secured together after both have been removed from the form and the bottom and top thereof are open so that the stitching machine can readily extend inside of the upper, and various overlays, cut-outs, or the like, may be stitched in position with a minimum amount of effort and labor.

After the upper containing my lining has been formed in the manner stated, the shoe 80 may be lasted or made up by any of the well-known methods, such as welt, McKay, turned, or stitched down. The completed 85 shoe is shown at 8.

If it is found necessary the retainer strip 3 may be cut away at the heel or elsewhere, so that the lining may take the shape of the last. The portion not cut away will 90 prevent the rest of the lining from stretching. That is, the retainer is practically non-stretchable while the leather, or the like forming the lining, will readily give to conform to the shape of the last. Therefore, 95

the retainer is cut at the desired point or points, and the leather will then readily extend to form the curve of the heel, or any other extending or curved portion of the 5 last.

While I have described a seamless lining I may also provide a pieced lining formed in the manner above stated.

If it is found necessary I may insert a 10 step in my method of forming linings after said lining has been formed over the die, this step consisting of applying heat to the lining so that it will be contracted about the die or form to conform exactly to the 15 shape thereof. This application of heat may be through ironing or similar process, and the ironing occurs while the lining is held in shape on the form. After the ironing step the retainer is placed on the lining, as previously stated.

Having described my invention, I claim:

1. A seamless lining for shoes comprising

a strip of shaped material, retainer means on said lining, and means to secure said retainer means to the lining, whereby the 25 lining is held in shape prior to lasting.

2. A lining for shoes comprising a strip of material, a retainer strip secured to the lining, said retainer strip being cut away to permit the lining to conform to the last, 30 and said retainer strip being stitched to the lining adjacent the lower end thereof.

3. A lining for shoes comprising a strip of material, a retainer strip secured to the lining, and means to secure said retainer 35 strip to the lining whereby the lining is prevented from stretching over the areas covered by the retainer, said retainer strip being partially cut away to permit the lining to conform to the last. 40

In testimony whereof, I affix my signature,

JOHN EMERSON SCOTT.
